Attorney

UNITED STATES PATENT OFFICE.

JOSEPH M. SALADINER, OF BRYAN, TEXAS.

SEED AND POISON POUCH.

Application filed July 1, 1922. Serial No. 572,133.

To all whom it may concern:

Be it known that I, JOSEPH M. SALADINER, a citizen of the United States, residing at Bryan, in the county of Brazos and State 5 of Texas, have invented a new and useful Seed and Poison Pouch, of which the following is a specification.

This invention relates to a combined pouch and sifter.

10 The object of the invention is to provide a device of this character in which dusty material may be scooped up and sifted and the dust confined in a container which may be closed dust-tight to prevent the contents 15 from escaping to the atmosphere, rendering it particularly useful in connection with poisonous powders or for sifting out seed and the like which have been treated with poisonous powders.

20 Another object is to provide a simple and efficient combined scoop and sifter, the scoop having a gravity closure equipped with opening means conveniently located for manipulation by the user.

25 Another object is to provide an improved sifter detachably connected with the scoop and having means for cooperation with the scoop to clamp a container between them.

With the foregoing and other objects in 30 view which will appear as the description proceeds, the invention resides in the combination and arrangement of parts and in the details of construction hereinafter described and claimed, it being understood

35 that changes in the precise embodiment of the invention herein disclosed, may be made within the scope of what is claimed without departing from the spirit of the invention.

In the accompanying drawing:—

40 Figure 1 represents a side elevation of a device constructed in accordance with this invention with the closure shown in open position.

Fig. 2 is a top plan view of the sifter used 45 in connection with the device.

Fig. 3 is a side elevation of the sifter.

Fig. 4 is a detail transverse section taken on the line 4—4 of Fig. 1.

In the embodiment illustrated, a container 50 is shown in the form of a pouch 1 constructed of any suitable dust-tight material such as canvas or the like, and which is equipped with a handle 2 secured to one side thereof and having a reduced neck 3 55 provided with a cord 4 for securing the mouth of the container after it has been

disengaged from the scoop 5 in connection with which it is designed to be used.

This scoop 5 is made in the form of a tubular member, the front end of which is 60 inclined or beveled transversely as shown at 6 and equipped with a gravity closure 7 hingedly connected at 8 to the beveled mouth of the scoop, and which is adapted to normally drop by gravity into closed position. This closure 7 as shown is reinforced on its outer face and equipped with a laterally extending eye 9 spaced inwardly from the hinged connection 8 and with which is engaged a rod 10 for opening the closure. 70 This rod 10 is mounted to slide in a keeper 11 carried by an arm 12 extending laterally and then rearwardly parallel with the inner end of the scoop 5.

The inner end of scoop 5 has a collar 12^a 75 soldered thereto which carries the arm 12 and hinge carrying extension 8. This collar and the inner end of the scoop have a longitudinally extending slot 13 opening through said end and around said end is an annular 80 inwardly opening trough 14 for a purpose presently to be described.

Detachably mounted in the scoop 5 is a sifter 15 made in the form of a tubular member of a cross sectional contour conforming to that of the scoop 5 in which it is designed to be mounted, and which is open at one end and closed at the other by a foraminous screen 18, the mesh of which may vary 85 according to the use of the device.

A pair of laterally spaced rods 19 and 20 arranged in parallel relation over the screened covering 18 are spaced therefrom a suitable distance, to permit a plurality of scrapers 20 to reciprocate thereon. These scrapers 20 are here shown in the form of metal plates threaded on said rods and carried by a reciprocating member in the form of a rod 21 having at its outer end a finger grip 22 in the form of a loop and equipped at its inner end with spacing sleeves 21^a and nuts 21^b to hold the scrapers 20^a assembled. One side wall of the sifter 15 is apertured as shown at 23 and which is designed to register with a cooperating aperture 5^a in the inner end of scoop 5 to receive a screw for detachably connecting the sifter with the scoop. An annular rib 17 is formed on the outer face of the body of the sifter near its outer end, and is designed to fit in the trough 14 on the inner face of the scoop 5 100 so that when the sifter is inserted in the

scoop 5, the registering rib and groove will operate to clampingly engage and to hold between them the mouth of the pouch 1, the cord 4 carried by said pouch being threaded 5 through an opening in the scoop as is shown clearly in Fig. 1.

In the use of this device, the pouch or sack 1 is first secured to the scoop 5 by inserting the mouth thereof between the rear end of 10 said scoop and the sifter 15 and clampingly connecting it between them. The screw which secures the sifter to the scoop is then inserted through the registering apertures 5^a and 23 therein, and the device is ready 15 for use. The material to be sifted is scooped up after the closure 7 is opened in the manner shown in Fig. 1, and the closure then drops, confining within the scoop 5, such material which is sifted by reciprocating the 20 member 21 which operates the scrapers 20^a and the sifted material passes through the screen 18 into the pouch 1 and after sufficient material has been sifted into said container, it may be removed from the scoop and the 25 mouth secured by wrapping the cord 4 around it so as to prevent all possibility of its contents escaping to the atmosphere.

After this container 1 has been removed and closed in the manner above described, 30 another container may be substituted and the operation repeated.

I claim:—

1. In a device of the class described, a tu-

bular filling member having a hinged closure at one end, a sifter removably mounted 35 in the other end of said member, said member and sifter having cooperating clamping elements to hold them engaged, and a container having a mouth for insertion between said sifter and member and to be clampingly 40 held thereby.

2. In a device of the class described, a tubular filling member having a hinged closure at one end, a sifter removably mounted 45 in the other end of said member, said sifter and member one having a rib and the other a groove to interlockingly engage to hold 50 said members together, and a container having a mouth to fit between said sifter and member and be clampingly held thereby.

3. The combination with a tubular member having a sifter removably mounted therein and comprising a tubular body member open at one end and having a foraminous 55 closure at its other end, a pair of parallel laterally spaced rods arranged over said closure and spaced therefrom, scrapers mounted to slide on said rods, and an actuating rod connected with said scrapers.

In testimony that I claim the foregoing 60 as my own, I have hereto affixed my signature in the presence of a witness.

JOSEPH M. SALADINER.

Witness:

JEFF. FORRER.
